UNITED STATES PATENT OFFICE.

BURT E. LLOYD, OF MONTCLAIR, NEW JERSEY.

SOUNDING FIGURE TOY.

Application filed March 26, 1926 Serial No. 97,523.

The object of this invention is to produce dolls or toys which, by applying pressure thereto, will cry or say ma-ma and will also simultaneously move its arms to cause the hands to clap or otherwise move.

Another object of this invention is to produce a doll with a minimum amount of stuffing therein and to build the doll upon a casing which contains therein a suitable sound producing device and the arm or limb actuating mechanism.

In the drawings Fig. 1 is a front elevation of a doll partly in section; Fig. 2 a horizontal section on line 2—2 of Fig. 1; Fig. 3 is a front elevation of the casing containing the sound producing and arm moving mechanism; Fig. 4 is a side elevation of Fig. 3; Fig. 5 is a vertical section on line 5—5 of Fig. 1; Fig. 6 is a front elevation of a doll partly in section showing a ma-ma voice; Fig. 7 horizontal section on line 7—7 of Fig. 6; Fig. 8 is a front elevation of the casing containing the operating mechanism; Fig. 9 is a sectional view on line 9—9 of Fig. 8; Fig. 10 is a side elevation of Fig. 8.

The doll comprises the body A, head B, arms C and legs D. The body, arms and legs are formed with an outer covering E made of suitable fabric. The entire doll is built around a casing G, made of cardboard, sheet metal or the like, formed to substantially doll body shape. The lower portion H of the casing G is formed to substantially buttock shape either as an integral portion of the casing or as a separate part secured to the bottom of the casing G. In the latter instance it may be made of wood or molded paper pulp, or other composition. The head B of the doll is suitably secured to the top of the casing G with the fabric E secured to the neck of the doll and the arms C and legs D supported with cotton or the like and sewn at the appropriate places to the fabric covering E. The arms and legs by reason of their attachment to the fabric E are loosely joined so that they will be readily movable.

The sound producing device 1 is secured to the casing G by suitable means such as the rivet 2 or the pin 2^a. A crier is inserted in the casing in one example of the invention (see Figs. 1 to 5) and a ma-ma voice in a modification (see Figs. 6, 7, 8, 9 and 10). The crier consists of the usual heads 3, 3^a, the attached rubberized fabric 4 forming a bellows, the reed 5 and the spring 6 contacting with the heads 3, 3^a in order to normally separate

them and to keep the bellows extended. A presser 7, preferably in the shape of a button, is secured to the head 3^a, which presser may be made of wood or a section of cardboard tubing, and normally projects through an opening 8 in the fabric of the body A and through an opening 9 in the casing G, preferably below the lowermost edge of the extended arms C. The presser 7 is, therefore, partly inside of the fabric E and partly outside thereof in an accessible position beneath the doll clothing but does not extend so far from the doll body as to press the doll clothing outwardly. The crier is actuated by pressure on the presser 7 through the doll clothing. Depending upon which end of the reed 5 is located nearest the sound escape opening the voice will be sounded either as the bellows is collapsed, or as it is allowed to extend, under influence of the spring 6, after having been collapsed, as is well understood in this art. The spring 6 when pressure is removed from the presser 7 will return the crier to normal position and will force the end of the presser 7 outwardly through the opening 8.

It is preferred to make the opening 9 in the body G considerably larger than the diameter of the presser 7 so that it can be pressed sideways in order to depress one side of the crier head 3^a more than the other side, thereby effecting movement of one arm while leaving the other arm substantially stationary, as more fully described hereafter. Arm operating mechanisms 10 are carried by the casing G and comprise the arm supports 11, which pass into the arms of the doll. The arm operating mechanisms 11, are carried by the shaft portions 12 secured in the bearings 13 which are formed out of the sides of the casing G. The continuations of the shafts 12 form the arms 14 which are embraced by the hooks 15 the ends of which pierce the presser 7. When the bellows is collapsed the shafts 12 are rocked resulting in the movement of the arms from the extended position shown in Fig. 4 to the clapping position shown in dotted lines in Figs. 2 and 7.

Upon pressure being applied to the presser 7 the bellows is collapsed and the hands are caused to clap, upon release of the presser air is drawn into the bellows which is extended under pressure of the spring 6, resulting in the sounding of the voice and the return of the arms to extended position. The voice may be actuated as the hands are brought together by changing the position of the sound pro-

ducer 5 so that the open end of the reed cup is inside of the housing 16 and the free end within the bellows chamber.

The voice may be caused to sound and but 5 one arm moved (the other arm remaining substantially still) by pushing the presser 7 sideways across the opening 9 so that one side of the bellows head 3^a is depressed to a substantial degree and the other side but slightly. 10 Pushing the presser 7 sideways in the direction of the arrow in Fig. 2 will result in the left arm swinging forwardly and holding the right arm substantially still and by pushing the presser in the opposite direction the right 15 arm will be caused to swing forwardly and the left arm held substantially still. The front 17 of the casing G is secured to the body of the casing by the ears 18 and the slits 19 are formed at the upper portion of the front 20 17 to permit free swinging of the arm supports 11.

A ma-ma voice type of doll is illustrated in Figs. 6 to 10 in which the voice articulates ma-ma simultaneously with the actuation of 25 the arms. The ma-ma voice comprises the post 20 upon which slides the head 3^a and upon which post the disk washers 21 are carried. When the device is collapsed by pressure on the hollow presser 7 the washers 21 30 pass through the sound escape opening 22 and articulate the sound escaping therethrough, which sound then escapes through the apertures 23 in the sides of the hollow presser 7. The arm operating mechanisms 10 are substantially like that shown in Figs. 1 to 5 and 35 comprise the arm supports 11, the shaft portions 12 which rock in the bearings 13. The shafts 12 are bent inwardly as indicated in Fig. 6 so that they lie in the path of the two 40 arms 24 which are secured in the head 3^a. The lower portions of the shafts 12 have hooks 25 formed therein which carry the respective ends of a coil spring 26, which coil spring holds the arm operating mechanism in such a 45 position as to keep the arms of the doll extended outwardly from the shoulders. When the presser 7 is pushed inwardly the bellows is collapsed and the sound escaping from the reed 5 is articulated by the disks 12 and at the 50 same time the arm operating mechanism is operated to cause the hands to clap as illustrated in Fig. 7.

A bar or brace 27, preferably of wood, is secured at the upper end of the casing G. A 55 fibre or cardboard disk 28 is glued to the underside of the doll's head to close the neck thereof and through which disk a bolt 29 passes. (See Fig. 5.) The bolt 29 also passes through a hole in the brace 27 and is 60 secured in that position to provide a bearing upon which the doll head may be turned. The fabric E is drawn fairly tight over the casing G and the end thereof secured with the usual twisted wire in the groove 30 formed in 65 the neck of the doll. An alternative struc-

ture for attaching the doll head to the casing G is shown in Figs. 6 to 10 wherein a block 32 which passes into the doll neck is secured by the pin 33 to the brace 27, and a cross pin, 70 34 passes through the side walls of the neck of the doll and through the block 32, whereby the head is pivoted to the casing G. In order to fill out the back of the doll a thin layer of 75 cotton is packed between the back of the casing G and the fabric covering forming the back of the doll.

I claim:

1. A doll comprising a body, a casing in the body, a sound producing device arranged transversely, from front to rear, in the casing, 80 one of the heads of said sound producing device being in fixed position, the other head thereof being movable, a post arranged in the sound producing device, a sound escape opening in the movable head, means on the post to articulate the sound issuing therefrom, a hollow presser over the upper end of the post and secured to said movable head, arms secured to the movable head and extending outwardly 85 therefrom, arm supports swingingly mounted on the casing and having portions extending into the arms of the doll and portions extending into the path of movement of the arms secured to the movable head, a spring normally tending to hold the arms in normal position 90 and the sound producing device in extended position, said arms being movable and the sound producing device collapsible by pressure on the presser against the pressure of the 95 spring.

2. A doll comprising a body, a casing in the body, a sound producing device arranged transversely, from front to rear, in the casing, 100 one of the heads of said sound producing device being in fixed position, the other head thereof being movable, a post arranged in the sound producing device, a sound escape opening in the movable head, means to articulate the sound issuing therefrom, a hollow presser over the upper end of the post, said presser 105 projecting into the casing and having connection with the movable head, arms secured to the movable head and extending outwardly therefrom, arm supports swingingly mounted on the casing and having portions extending into the arms of the doll and portions extending into the path of movement of the arms secured to the movable head, a spring normally tending to hold the arms in normal position 110 and the sound producing device in extended position, said arms being movable and the sound producing device collapsible by pressure on the movable presser against the pressure of the spring, the upper end of 115 said post being projected into the hollow space of the presser when the sound producing device collapses and sound escape openings in the presser to permit the escape of the articulated sound.

3. A doll comprising a body, a casing in the 120

body, a fabric covering over the casing, a sound producing device arranged transversely, from front to rear, in the casing, one of the heads of said sound producing device being in fixed position, the other head thereof being movable, a post arranged in the sound producing device, a sound escape opening in the movable head, means to articulate the sound issuing therefrom, a hollow presser over the upper end of the post, said presser projecting into the casing and having connection with the movable head, an aperture through the fabric and in line with the presser and through which the forward end of the presser is projected, arms secured to the movable head and extending outwardly therefrom, arm supports swingingly mounted on the casing and having portions extending into the arms of the doll and portions extending into the path of movement of the arms secured to the movable head, a spring normally tending to hold the arms in normal position and the sound producing device in extended position, said arms being movable and the sound producing device collapsible by pressure on the presser against the pressure of the spring, the upper end of said post being projected into the hollow space of the

presser when the sound producing device collapses and sound escape openings in the presser to permit the escape of the articulated sound. 30

4. A doll comprising a body, a casing in the body, a sound producing device arranged transversely, from front to rear, in the casing, a spring normally tending to extend one head of the sound producing device, the other head thereof being in fixed position, an arm support carrying a doll arm, arm operating mechanism, said arm operating mechanism comprising a vertically arranged shaft rockingly mounted at a plurality of points on said casing, an arm extending from said shaft and partaking of the movement of said shaft, an actuating member carried by the movable head of the sound producing device, said actuating member being movable in the same path as the arm carried by said shaft, a presser carried by the movable head, said spring normally holding the sound producing device in extended position, said sound producing device and arm operating mechanism being operable by manual pressure against the presser. 35 40 45 50

In testimony whereof I have hereunto set my hand.

BURT E. LLOYD.
